Atty.

UNITED STATES PATENT OFFICE.

FRANK H. SOVEREIGN, OF VALLEJO, CALIFORNIA.

RATCHET.

Application filed November 27, 1922. Serial No. 603,614.

To all whom it may concern:

Be it known that I, FRANK H. SOVEREIGN, a citizen of the United States, and residing in the city of Vallejo, county of Solano, and State of California, have invented a new and useful Improvement in a Ratchet, of which the following is a specification.

My invention relates to improvements in ratchets and the like wherein an actuating member is arranged to rotate a body when turned in one direction and to be independently rotatable when turned in the opposite direction.

The primary object of my invention is to provide an improved ratchet.

Another object is to provide an improved device of the character described affording increased strength and durability.

A further object is to provide an improved construction designed to give a positive connection which cannot slip when pressure is being applied.

A still further object is to provide an improved construction which may be easily made and assembled and which will afford a light and compact tool of great strength.

I accomplish these and other objects by means of the device disclosed in the drawings forming a part of the present specification and drawings in which like characters of reference are used to designate similar parts throughout said specification and drawings, and in which:

Fig. 1 is a broken side elevation partly in section of my improved ratchet.

Fig. 2 is a broken plan view of the actuating member.

Fig. 3 is a broken side elevation of the ratchet in an inverted position showing the application to an object to be turned.

Fig. 4 is a broken side elevation showing a different means for connecting the body to an object to be turned.

Fig. 5 is a side elevation partly in section of the body.

Fig. 6 is a broken longitudinal section of the actuating member.

Fig. 7 is a broken plan view of the ratchet as shown in Fig. 1.

Referring to the drawings the numeral 1 is used to designate in general the body portion of a ratchet, said body having a plurality of spiral teeth 2 formed thereon. An actuating member 3 is mounted upon the body 1 and arranged for sliding and rotative movement thereon. A plurality of spiral

teeth 4 are internally formed upon the member 3 to correspond with the teeth 2 of the body.

A member 6 is slidably mounted within an axial recess 7 formed in the body 1 and is provided with arms 8 extending laterally through a slot 9 into engagement with the actuating member 3. A spring 11 is mounted within the outer portion of the recess 7 to normally exert a slight pressure against the member 6 whereby the arms 8 will be caused to advance the actuating member along the body 1 and cause the teeth 4 to become meshed with the teeth 2 of the body. A plug 12 is threaded into the outer end of the recess to retain the spring compressed against the member 6. The arms 8 are preferably formed by the protruding ends of a pin fitted into a transverse aperture formed in the member 6.

Extensions 13 and 14 are formed upon the ends of the body to engage an object to be turned. These extensions may be made of any desired shape adapted to meet the requirement of any particular method of application. In the drawings I have illustrated the extensions as square shanks such as are adapted for insertion into the ends of socket wrenches and the like. However, the extensions may be recessed as shown in Fig. 4 to fit over an object to be turned, or otherwise adapted for connection with an object or tool to be rotated by a ratchet in the well known manner. In this connection it should be noted that the extensions upon opposite ends of the body 1 should be the same so that either end of the body may be applied to the object to be turned for a reason that will hereinafter appear.

The operation of my improved ratchet is as follows: The actuating member being mounted upon the body as above described, the body is connected to the object to be turned by means of one of the extensions 100 formed upon the ends thereof. The actuating member is now moved in the direction of incline of the teeth 2 and the teeth 4 meshing therewith the natural tendency of such movement being to advance the actuating member along the spiral teeth of the body, until further movement in that direction is prevented when a shoulder 16 formed within the member 3 engages the inner ends of the teeth 2. Further movement of the actuating member then causes each tooth 4 to bear against the adjacent tooth of

the body, the body and the object to which it is connected being thereby caused to turn with the actuating member. When the actuating member is now turned in the opposite direction to the position shown in dotted lines in Fig. 1 and 7 of the drawings, the pitch of the teeth will cause the member to be moved longitudinally along the body until the teeth 4 disengage the teeth 2, thus 10 permitting independent rotation of the actuating member. The spring 11 causes the member to return to operative engagement with the teeth 2 as soon as the rearward movement of the actuating member 15 has been completed and the turning force released.

From the above description it will be seen that each of the teeth of the body is 20 engaged by a tooth of the actuating member when turned in one direction, and released when the actuating member is turned in the opposite direction. By inverting the body 1 with respect to the object to be turned the ratchet may be operated to turn the 25 object in either direction. Thus when the ratchet is positioned in the manner shown in Fig. 1 of the drawing a movement of the actuating member from left to right will 30 operate to turn the body and any object connected thereto, while by inverting the ratchet as shown in Fig. 3, a movement from right to left will cause the teeth to engage and move the body. The plurality of teeth 35 each having a relatively large surface engaged by one of the teeth of the actuating member gives great strength to the device as the several teeth combine to effect the desired turning movement and the failure of any one tooth cannot affect the operativeness 40 of the device as the remainder of the teeth will be unaffected by such failure. Furthermore, all possibility of slippage, such as often occurs in the case of ratchets 45 operating upon the ordinary spring actuated pawl principle, is overcome, as the teeth of the body are normally entirely enclosed in the actuating member in meshing relation with the teeth thereof so that slippage can only occur in event of the shearing off of 50 all the teeth. The combined strength of the several teeth is so great that the tool may be made of a relative light construction without reducing the effective strength of the device below the requirements of ordinary 55 usage.

The pitch of the teeth is designed to give smooth, easy movement of the actuating member as the teeth are moved into engaging and releasing relation with the 60 teeth of the body without causing an excessive amount of lost motion due to the amount of movement necessary to move the teeth of the actuating member from operative to releasing relation with the body.

65 The construction and arrangement of the

device as shown in the drawings, while embodying what I now consider to be the preferred construction because of the ease and economy with which it may be manufactured, is subject to many modifications. I therefore, do not desire to restrict myself to the precise disclosure which I have herein made, but wish to avail myself of all modifications which may fall within the scope of the appended claims.

Having thus described my invention what I claim as new and desire to secure by Letters Patent is:

1. A ratchet comprising a body having spiral teeth formed thereon; an actuating member mounted upon said body and provided with teeth corresponding to the teeth of the body, said teeth being arranged to engage the teeth of the body and cause said body to be rotated when the member is turned in one direction and to be moved to disengaging relation permitting independent rotation of the actuating member when turned in the opposite direction; and means for connecting either end of the body to an object to be turned whereby said object may be turned in either direction.

2. A ratchet comprising a body having spiral teeth formed thereon; an actuating member mounted upon said body and provided with teeth corresponding to the teeth of the body, said teeth being arranged to engage the teeth of the body and cause said body to be rotated when the member is turned in one direction and to be moved to disengaging relation permitting independent rotation of the actuating member when turned in the opposite direction; means for normally moving the member into operative position with the teeth thereof in meshing relation with the teeth of the body; and means formed upon the body for detachably connecting either end of said body with an object to be turned.

3. A ratchet comprising a body having a plurality of spiral teeth formed thereon; an actuating member slidably and rotatably mounted upon the body and provided with a plurality of teeth corresponding to the teeth of the body; a spring mounted upon the body and engaging the actuating member for normally moving said member into an operative position with the teeth thereof in meshing relation with the teeth of the body whereby the body may be rotated when the member is turned in one direction, a turning of said member in the opposite direction causing the actuating member to be moved longitudinally away from the teeth against the pressure of the spring into an independently rotatable position; and means formed upon opposite ends of the body for detachably engaging an object to be turned whereby the object may be turned in either direction.

4. A ratchet comprising a body having an axial recess and a longitudinally disposed slot formed therein and provided with a plurality of spiral teeth; an actuating member slidably and rotatably mounted upon the body and provided with a plurality of teeth corresponding to the teeth of the body; a member slidably mounted within the axial recess of the body and provided with arms 10 extending outwardly through the sides of the slot into engagement with the actuating member; and a spring mounted within the recess and arranged to exert a pressure against the member within the recess whereby the arms of said member may be caused to advance the actuating member into a normally operative position with the teeth thereof in meshing relation with the teeth 15 of the body.
5. A ratchet comprising a body having an axial recess and a longitudinally disposed
- slot formed therein and provided with a plurality of spiral teeth; an actuating member slidably and rotatably mounted upon the body and provided with a plurality of teeth corresponding to the teeth of the body; a member slidably mounted within the axial recess of the body and provided with arms 20 extending outwardly through the sides of the slot into engagement with the actuating member; and a spring mounted within the recess and arranged to exert a pressure against the member within the recess whereby the arms of said member may be caused to advance the actuating member into a normally operative position with the teeth thereof in meshing relation with the teeth 25 of the body; and means for connecting the body to an object to be turned.
6. A ratchet comprising a body having an axial recess and a longitudinally disposed slot formed therein and provided with a plurality of spiral teeth; an actuating member slidably and rotatably mounted upon the body and provided with a plurality of teeth corresponding to the teeth of the body; a member slidably mounted within the axial recess of the body and provided with arms 30 extending outwardly through the sides of the slot into engagement with the actuating member; and a spring mounted within the recess and arranged to exert a pressure against the member within the recess whereby the arms of said member may be caused to advance the actuating member into a normally operative position with the teeth thereof in meshing relation with the teeth 35 of the body; and means for connecting the body to an object to be turned.

In witness whereof I hereunto set my 40
signature.

FRANK H. SOVEREIGN.
